UNITED STATES PATENT OFFICE.

WALTER T. DAVIS, OF WHEELING, WEST VIRGINIA, ASSIGNOR TO WHEELING STAMPING COMPANY, OF WHEELING, WEST VIRGINIA, A CORPORATION OF WEST VIRGINIA.

FEED HOPPER.

Application filed March 12, 1928. Serial No. 94,362.

The present invention relates to the art of blank separating and feeding and more particularly to an improved hopper by means of which blanks of the desired nature may be supplied as desired to a press or other metal working machine adapted to operate thereon.

In some industries, and particularly in those industries requiring the use of comparatively soft blanks such as lead, tin, lead and tin, aluminum or the like, considerable difficulty is experienced in the proper separation and feeding of the blanks as required. This is not only due to the tendency of the blanks to become distorted during handling, but also due to their tendency to build up or bridge the discharge opening, thereby preventing further feeding. This is particularly true of hoppers which operate about a vertical axis, although the condition may be minimized to some extent by the proper shaping of the side walls of the hopper.

It is one of the objects of the present invention to provide a hopper which will successively feed blanks of any desired nature without distortion thereof and at the speed required.

Another object of the invention is to provide a hopper which is adjustable in such manner that it may cooperate and feed blanks of different diameter at will, thereby increasing the utility of the same.

Still another object of the invention is to provide a hopper which will serve to tumble the blanks to some extent to thereby remove sharp edges while enabling the hopper to be refilled at will while it is in operation.

In the accompanying drawings there are shown for purposes of illustration only certain preferred embodiments of the present invention, it being understood that the drawings do not define the limits of my invention as changes in the construction and operation disclosed therein may be made without departing either from the spirit of the invention or the scope of my broader claims.

In the drawings:

Figure 1 is a side elevational view, partly broken away, of a metal working machine having a hopper constructed in accordance with the present invention applied thereto;

Figure 2 is a side elevation of the hopper of Figure 1, the view being taken from the opposite side of the hopper and showing a

horizontal mounting therefor in place of the vertical mounting of Figure 1;

Figure 3 is a vertical sectional view on the line III—III of Figure 2 looking in the direction of the arrows;

Figure 4 is a top plan view of the hopper of Figures 1 and 2, the filling shoe being removed from one of the hopper sections; and

Figure 5 is a vertical sectional view on the line V—V of Figure 3 looking in the direction of the arrows.

While a hopper constructed in accordance with the present invention is adaptable for use with a variety of different machines, it is herein illustrated as being applied to a press and more particularly to an extrusion press of the character commonly used in the manufacture, for example, of collapsible tubes, the blanks being delivered by the hopper in such cases obviously having the dimensions and characteristics required for the production of a tube. The utility of the invention, however, is not limited either with respect to the type of metal working machine or the size or characteristics of the blanks supplied. The metal working machine 2 has an operating shaft 3 which, in the event of a press, may be the eccentric shaft which operates the plunger. Suitably secured to the shaft is an eccentric 4 adapted to cooperate with a pitman 5 constituting a portion of the operating means for the blank feed mechanism whereby such mechanism is operated in unison or synchronism with the operation of the metal working machine.

Projecting laterally from the frame of the machine is a bracket 6 having mounted thereon a table 7 carrying bearings 8 for a horizontally extending shaft 9. This shaft 9 intermediate the bearings 8 which may project either vertically as shown in Figure 1 or horizontally as shown in Figures 2 and 3, carries a hopper section 10 and a hopper section 11. These sections are preferably of somewhat similar construction each embodying a central hub 12 and an end plate 13 from which the outwardly converging side walls 14 extend. The section 10 may have its hub portion 12 provided with set screws 15 by means of which this section may be clamped in any desired position. Extending outwardly from the flange 16 in which the conical wall 14 of the section 10 terminates

are inwardly extending agitating and guiding fingers 17, the fingers preferably projecting substantially radially of the hopper section as clearly shown in Figure 5. After 5 the section 10 has been secured in position, the section 11 may be clamped onto the shaft 9 in the desired spaced relation to the section 10 by means of the set screw 18, this set screw 10 being accessible exteriorly of the hopper as 10 is clearly apparent. The flange 19 on the section 11, corresponding to the flange 16, is preferably provided with recesses 20 adapted to receive the agitating and guiding fingers 17 as clearly shown in Figure 4 of 15 the drawings. By reason of this construction, the space S left between the adjacent faces of the flanges 16 and 19 may be of any desired width, the width being preferably slightly greater than the thickness of the 20 blanks B, indicated in dotted lines in Figure 2, being handled. This necessitates the passage of the blanks from the hopper in an edgewise position, and permits the hopper to be adjusted as required for use with 25 blanks of different dimensions.

Formed in the conical wall 14 of the section 10 is a filling window 21. It will be apparent that in order to permit the machine to be filled during operation of the 30 hopper while preventing the blanks within the hopper from spilling out, special arrangements are required. Such operation is permitted by providing a filling shoe 22 of a shape to closely conform to the contour of the section 10 and more particularly the 35 conical portion 14 thereof, the filling shoe carrying a feed chute 23. The feed chute 23 and the filling shoe 22 each has an opening substantially the same size as that of the 40 opening 21, the rotation of the hopper bringing all of these openings into registration at predetermined times, it being understood that the shoe 22 remains stationary. In order that an operator may know when the 45 respective openings are in alignment, the section 11 may be provided at any desired point therein with suitable indicating marks 24. When these marks substantially coincide with the position of the chute 23 blanks may 50 be poured into the chute without danger of jamming of the apparatus or cutting of the blanks between the trailing end of the feed opening 21 and the front end of the corresponding opening in the shoe 22.

For operating the hopper intermittently in accordance with the operation of the machine which it supplies, the shaft 9 may be provided with a ratchet wheel 25 adapted to cooperate with a pawl 26 carried by a pin 27 60 mounted in an arm 28 journaled on the shaft 9, all of the parts being held in the desired position and the shaft 9 being held against movement longitudinally by means of a clamping collar 29. One end of the pitman 65 5 before referred to is secured to the pin 27

whereby a predetermined stroke is imparted to the pawl 26 for each rotation of the shaft 3. The parts are held in the position to which they are moved by a holding pawl 30 normally urged into cooperative relation with 70 the ratchet wheel by a spring 31.

As the hopper rotates the blanks are fed toward the center of the hopper due to the inclination of the walls of the hopper sections. In this position they are engaged by 75 the agitating and guiding fingers 17 and separated in such manner that they flow individually into the space S between the sections. Preferably the hopper is operated in a direction indicated by the arrow in Figure 80 2 so that blanks in the space S are free to roll outwardly to the left as viewed in this figure into the collecting and guiding space 32 formed on one side by a stationary plate 33, on the opposite side by a similar plate 34 85 having windows 35 therein and on the back by an adjustable curved guide 36. The guide 36 is preferably adjusted by means of the bolts 36' so as to provide a space 32 having a width substantially equal to but slightly 90 greater than the diameter of the blanks being handled. Throughout the remainder of the periphery of the hopper, the space S is effectively closed by a curved closure plate 37 preventing any of the blanks from being 95 discharged from the hopper until such blanks are in position to enter the guiding space 32. In this position the blanks tend to roll down the fingers 17 and keep the space 32 filled up to a point substantially 100 coinciding with the horizontal axis of the hopper.

Blanks delivered into the space 32 pass downwardly, as indicated in Figure 2 until their movement is arrested by an adjustable stop 38, the adjustment of which is varied in accordance with the diameter of the blanks being handled. In this position the blanks are engaged by a pusher 39 and forced to the right into a position where 105 they are engaged by the spring pressed retaining plate 40. A blank is held by this retaining plate until a second blank is pushed laterally in such manner as to discharge the first and become itself retained by the plate. The pusher 39 is operated in unison with the ratchet 25 by providing a link 41 connected at one end to the pin 27 and at its opposite end provided with a slot 42 adapted to receive the pin 43 110 extending laterally from one arm of a suitable bell crank lever 44. This bell crank lever may be journaled on a pin 45 carried by the plate 33, and may have its opposite end provided with a pin 46 working in a slot 47 in the outer end of the pusher 39. The direction of movement of the pusher may be controlled in any desired manner, as, for example, by suitable guides 48. As 115 the blanks are successively released by the 120

plate 40, they roll down a chute 49 leading to any desired point of use.

In the event a defective blank is delivered by the hopper, it is visible while positioned above the adjustable stop 38 and may be easily removed by stopping the rotation of the hopper and dropping the adjustable stop. Thereafter the apparatus may continue in operation as required.

Certain advantages of the present invention arise from the provision of a hopper for blanks comprising adjustable sections adapted to provide a discharge opening therebetween and adjustable at will to vary the width of the discharge opening.

Other objects of the invention arise from the provision of a hopper having a horizontal axis of rotation and provided with inwardly extending agitating and guiding fingers adapted to direct the blanks toward a suitable discharge opening or openings properly positioned with respect thereto.

Further advantages of the invention arise from the provision of an adjustable guide adapted to receive blanks discharged by the hopper whereby the hopper is adapted for the handling of blanks of different diameter as well as different thickness.

Still further advantages arise from the provision of a hopper and a filling chute substantially conforming to a portion of the contour of at least a portion thereof whereby the hopper may be filled while in operation.

Still further advantages are inherent in the use of blank engaging and feeding means permitting a clear view of the blanks as desired whereby their character and suitability may be visually inspected.

I claim:

1. A feed hopper, comprising a shaft, relatively adjustable sections each carried by said shaft and providing a discharge space therebetween, and means for securing each of said sections to said shaft.

2. A feed hopper, comprising rotatable opposing sections having oppositely inclined walls, at least one of said sections being adjustable to provide a discharge space between the sections, means for holding said sections in axial alinement during adjustment thereof and hopper means delivering into one of said sections.

3. A feed hopper, comprising rotatable opposing sections having oppositely inclined walls, at least one of said sections being adjustable to provide a discharge space between the sections, and guiding means cooperating with said discharge space, said guiding means comprising inwardly extending agitating fingers rotatable with said sections.

4. A feed hopper, comprising opposed hopper sections having a discharge space therebetween, a curve guide adapted to receive blanks discharged through said space,

and means for adjusting said guide radially toward and from the axis of said sections to cooperate with blanks of different diameter.

5. A feed hopper, comprising rotatable opposed hopper sections having a discharge space therebetween, a curved guide adapted to receive blanks discharged through said space during rotation of said sections, and means for adjusting said guide to cooperate with blanks of different diameter, one of said hopper sections being adjustable to vary the width of said discharge space to permit the hopper to cooperate with blanks of different widths.

6. A hopper for blank feeding, comprising a substantially horizontally disposed operating member, opposed sections each directly carried thereby and secured thereto, and providing a discharge space in a plane substantially normal to the axis of said operating member, and guiding means for the blanks delivered by said sections.

7. A hopper for blank feeding, comprising a substantially horizontally disposed operating member, opposed sections each directly carried thereby and secured thereto, and providing a discharge space in a plane substantially normal to the axis of said operating member, and guiding means for the blanks delivered by said sections, said guiding means being adjustable to permit the same to cooperate with blanks of different diameter.

8. A feed hopper, comprising a horizontally positioned hopper section, means adjustably cooperating therewith and supported independently thereof to provide a peripheral discharge space for blanks carried by said section, and guiding means cooperating with said discharge space.

9. A feed hopper, comprising a horizontally positioned hopper section, means adjustably cooperating therewith to provide a peripheral discharge space for blanks carried by said section, and guiding means cooperating with said discharge space, said guiding means comprising inwardly extending fingers carried by said hopper section.

10. A feed hopper, comprising a horizontally positioned hopper section, means adjustably cooperating therewith to provide a peripheral discharge space for blanks carried by said section, and guiding means cooperating with said discharge space, said hopper section having a filling opening therein, and a filling shoe embracing said section and constructed to permit filling of said section during operation thereof.

11. Blank feeding means, comprising a hopper having a substantially vertically arranged discharge opening, and means for feeding blanks to the interior of said hopper in a direction substantially parallel to the plane of said opening.

12. Blank feeding means, comprising a rotating feed hopper having a substantially vertically disposed discharge opening, and a plurality of guiding fingers extending inwardly of said hopper and adapted to deliver blanks to said opening. 16. A feed hopper, comprising independently supported relatively adjustable sections providing a substantially vertically arranged discharge opening therebetween, means for rotating said sections, and guiding means permanently secured to said hopper and cooperating with said opening to effect the feeding of blanks therethrough irrespective of the relative adjustment of said sections. 35
13. Blank feeding means, comprising a rotating feed hopper having a substantially vertically disposed discharge opening, and a plurality of guiding fingers extending inwardly of said hopper and adapted to deliver blanks to said opening, said hopper embodying means for adjusting the width of said opening to permit the passage of blanks of different widths therethrough. 17. Blank feeding means comprising a sectional hopper having a substantially vertically arranged discharge opening between said sections, means for rotating said hopper, and a guiding finger cooperating with said opening, said guiding finger being carried entirely by one of the hopper sections. 40
14. Blank feeding means, comprising a hopper, an adjustable guide cooperating therewith to provide a guiding space of the width required for the blanks being handled, means forming a stop for blanks in said space and permitting inspection thereof, and means for discharging blanks from a position in which they may be inspected. 18. Blank feeding means, comprising a shaft, relatively separable hopper sections each carried by said shaft and providing a discharge opening therebetween, and means cooperating with one of said sections for effecting feeding of blanks thereto in a direction substantially parallel to the plane of said opening. 45
15. The combination with a metal working machine, of a feed hopper comprising a plurality of horizontally arranged oppositely disposed hopper sections, means for delivering blanks to one of said sections, means for adjusting the other of said sections independently of the first named section to provide a discharge space of variable width between the sections, and means for operating said sections in timed relation to the operation of said machine. 19. Blank feeding means, comprising a shaft, sections adjustably carried by said shaft, and a blank feeding shoe embracing one of said sections for feeding blanks thereto during rotation thereof. 50
- In testimony whereof I have hereunto set my hand. 60
